UNITED STATES PATENT OFFICE.

CHARLES H. JONES, OF PROVIDENCE, RHODE ISLAND, ASSIGNOR TO UNIVERSAL WINDING COMPANY, OF BOSTON, MASSACHUSETTS, A CORPORATION OF MASSACHUSETTS.

WINDING MACHINE.

Application filed May 4, 1927. Serial No. 188,809.

This invention relates to winding machines and particularly to the mechanism for starting and arresting the operation of the machine.

5 One object of the invention is to provide means for arresting the operation of the winding when the strand of yarn, thread or other material breaks or its supply is exhausted, combined with manually-controlled 10 means for restarting the operation of the machine after the yarn has been pieced up or its supply replenished.

A particular object of the invention is to provide a stopping-mechanism which is 15 proof against premature or unwarranted operation after the restarting of the machine, due to slackness of the strand of thread, yarn or other material feeding to the machine or from other causes.

20 A further object of the invention is to provide a starting- and stopping-mechanism for winding machines which is simple in construction, positive in action, and proof against derangement or getting out of order.

25 A preferred embodiment of the invention is described in the following specification and illustrated in the accompanying drawings. In the drawings:

Fig. 1 is a front elevation of one unit of 30 a winding machine, showing the essential elements thereof;

Fig. 2 is an end elevation of the same;

Fig. 3 is an end view showing the main 35 elements of the winding-mechanism and the starting- and stopping-mechanism illustrated in detail in connection therewith, the parts being shown in position after the winding has been arrested;

Fig. 4 is a similar view showing the parts 40 in position as the machine starts to operate; and

Fig. 5 is a perspective view in detail of 45 the trip- or knock-off lever of the stopping-mechanism.

The present invention is herein illustrated 50 by way of example as applied to a winding machine of the friction or drum-driven type in which a cop or package of yarn or thread is wound on a rotatable mandrel or holder and driven through frictional contact with the surface of a continuously rotating drum or drive-roll. In machines of this type the 55 yarn is traversed longitudinally of the mandrel or cop-holder by means of a recipro-

cating thread-guide, and to arrest the winding the cop or package is removed from contact with the drive-roll, and usually the thread or yarn is concurrently disengaged from the continuously reciprocating thread-guide. In general, the present invention 60 provides for arresting the winding operation in the manner last described and also for restarting the machine while controlling the stopping-mechanism to prevent premature or unwarranted operation thereof 65 before the thread or yarn has been picked up by the guide and caused to traverse on the package to take up the slack in the strand.

Referring to Figs. 1 and 2 of the drawings, 2 designates the rotatable cop-holder or mandrel which, as herein illustrated, is adapted for holding a conical paper shell or cop-tube α , shown in section in Fig. 1, to adapt it to bear against the surface of the 70 drive-roll or friction-drum 3. The cop-holder or mandrel 2 is freely rotatable on a dead-spindle 4 swiveled at the end of an arm 5 which forms the support for the holder as the latter moves away from the drive-roll 75 during the building of the mass of yarn on the tube α . The arm 5 is pivoted on a fixed rod or shaft 8 and the cop-holder spindle 4 is hinged at 9 to the outer end of an extension 10 projecting forwardly from the arm. 80 The extension 10 is provided with a stud or bearing 12 engaging a bore 13 in the arm 5, see Fig. 2, whereby the cop-holder is adapted to rock or tilt on an axis crossing the axis of the drive-roll 3 to maintain the surface of 85 the winding in contact therewith. The hinged joint 9 which connects the spindle 4 with the end of the extension 10 on the arm 5 provides for swinging the cop-holder forwardly to facilitate the placing of the cop-tube α thereon and the doffing of the completed package therefrom, the arrangement 90 of the above-described parts being of well known construction as heretofore employed in the present art.

The arm 5 is provided with a vertical extension or flange 14 carrying a weight 15 bolted to its side and acting to apply pressure to maintain the cop or package bearing against the drive-roll 3 to insure the proper frictional driving contact therewith. The arm 5 also has a downwardly extending flange 16 in the form of a quadrant disposed 100

with its curved edge concentric with the axis on which the arm swings. The circular rim of the quadrant 16 is grooved to receive a hardened steel ratchet 17 of arcuate shape secured in place by screws 18 and formed with teeth 19 on its lower face. The ratchet 17 provides means for controlling the swinging movement of the arm 5 during the recession of the cop-holder 2 from the drive-roll 3 as the winding builds up thereon, and also operates in connection with the stopping-mechanism of the machine to remove the cop or package from driving contact with the drive-roll in the manner as herein-
15 after more fully explained.

The drive-roll 3 is mounted fast on a horizontal shaft 23 journaled in bearings 24 supported on the brackets or members 25 which form a part of the machine frame. The
20 shaft 23 is continuously driven through suitable power connections not herein shown.

It will be understood that the shaft 23 extends longitudinally of the main frame of the machine which is adapted to support a
25 plurality of winding heads or units, each having its own drive-roll rotating with the shaft. Only one winding unit is shown in the present drawings, but the complete machine may comprise any suitable number
30 thereof arranged on opposite sides of the frame.

A second horizontal shaft 26, located below and at the rear of the drive-roll shaft 23, is journaled in bearing boxes 27 on the
35 frame-members 25 and is continuously driven to rotate the traverse-cams 30 for the several winding units. As shown more particularly in Figs. 1 and 2, each traverse-cam 30 is constructed with a helical rim 31 supported by spokes 32 extending from opposite hubs 33 which are fixedly secured on the shaft 26. The cams for the several winding heads are rotated continuously and operate to reciprocate the thread-guides of the
40 machine through connections as next described.

Each winding unit is provided with its own thread guide 35 comprising a curved arm 36 projecting upwardly from a slide or carriage 37. Referring to Fig. 1, the arm 36 is slotted at the top to receive a hardened guide-block 38 held in place by a screw 39, see Fig. 3, and provided with a groove 40 through which the strand *y* of yarn, thread or other material feeds. The guide-carriage or slide 37 is mounted to slide on a horizontal rod 41 and a flat bar 42 which extend between the brackets or frame-members 25. Projecting rearwardly from the slide 37 is a
50 stud 43 carrying a bowl or roller 45 which engages with the helical groove 46 in the cam 30. Through these connections the rotation of the cam 30 causes the thread-guide 35 to be reciprocated back and forth longitudinally of the drive-roll 3 to traverse the

strand *y* of yarn or other material as it feeds through the guide, whereby it is deposited in helical turns on the surface of the cop or package being wound. The strand of yarn or other material draws off
70 from a supply, usually arranged below the winding unit, and as it feeds to the thread-guide 35 tension is applied thereto through the use of any suitable means. As shown in Figs. 1 and 2, the present tension-device
75 comprises two rollers 47 and 48 carried at the end of an arm or bracket 49 secured to one of the frame-members 25. The strand *y* leads up over the roller 47 and under the roller 48 to divert its course to apply tension thereto, and thence it is drawn up across a thread-bail 50 and through the groove 40 in the thread-guide 35.

The thread-bail 50 consists of a length of wire bent into inverted U-shape as shown in Fig. 1 with its legs held in lugs or ears 51 on a tiltable frame or plate 55. The frame or plate 55 is rockably supported at the bottom on pins or studs 56 projecting from the sides of the frame-members 25. Through this arrangement the plate 55 constitutes a thread-lifter for raising the strand out of the groove 40 in the thread-guide 35 whereby to disengage the strand from the guide to arrest its traverse thereby. The thread-lifter 55 is operated by means of an arm or bar 60 pivoted at 58 to a lug 57 projecting from its rearward side. The arm 60 extends beneath the quadrant 16 and terminates in a pawl-like projection 61 adapted to engage successively with the teeth 19 on the ratchet 17 as the arm 5 swings upwardly under the movement of the cop-holder 2 during the growth in the winding. The rearward end of the arm 60 is maintained in yielding engagement with the teeth 19 on the ratchet 17 by means of a coiled spring 63 anchored to the frame-member 25 with its opposite end hooked around a pin 64 on the arm.

It will be noted by reference to Fig. 2 of the drawings that the thread-lifter 55 is normally held in inclined relation extending upwardly at the rear of the thread-guide 35 to maintain the thread-bail 50 in close proximity thereto. Adjustable means are provided for supporting the thread-lifter in this position resting against the frame-members 25. For this purpose I may employ screws 65 extending through bosses 66 on the back of the thread-lifter 55 with their ends bearing against inclined lips 67 on the frame-members 25. The screws 65 may be adjusted to set the thread-lifter 55 with its bail 50 in proper relation with respect to the thread-guide 35, and suitable check-nuts 68 are provided to lock the screws in adjusted position. It will be observed from the above that as the cop-holder 2 rises from the drive-roll 3 during the growth of the package wound on the holder the quad-

rant 16 is moved by and with the arm 5, whereby the teeth on the ratchet 17 are caused to engage successively with the pawl 61 at the end of the arm 60. Now, since the 5 thread-lifter 55 rests against the frame-members 25 the pawl 61 will act as a dog or 70 detent to restrain the arm 5 from swinging back or dropping down to lower the cop-holder. This dogging action prevents the 10 cop or bobbin from jumping or bounding on the drive-roll, due to inequalities in the surface of the winding or from other causes.

The stopping-mechanism of the machine is actuated by a trip- or knock-off lever 70, 15 illustrated in Figs. 1 to 4 and shown in detail in Fig. 5 of the drawings. The pin or rod 58 on which the lever 60 is pivoted is held in lugs 57 on the thread-lifter 55, as previously explained, and rockably 20 mounted on this rod in position between the lugs is the bell-crank 70, herein termed the trip- or knock-off lever. One arm 71 of the lever 70 extends forwardly through an opening 59 in the thread-lifter 55 and is formed 25 with a boss at its end carrying a wire or pin 73 adapted to be held in position bearing against the strand *y* as it draws between the tension-roll 48 and the thread-bail 50. This arm 71 is connected by a cross-strip 74 30 to the rearwardly extending arm 75 which acts as a faller or knock-off to rock the thread-lifter 55 and slide the arm 60. The arm 75 is formed with a depending weight-portion 76 and is normally suspended in the 35 position shown in Fig. 2 by the tension of the strand *y* drawing across the pin 73. When the strand *y* breaks or its supply is exhausted the pin 73 will be released, whereby the weighted arm 75 of the lever 70 will 40 drop down into the position illustrated in Fig. 3. As the knock-off arm 75 drops it is adapted to be engaged by a constantly oscillating rocker-arm 77 which serves as the power-means for operating the stopping- 45 mechanism of the machine.

The rocker-arm 77 is pivotally mounted on a stud 78 projecting from the side of the frame-member 25 and is formed with a forked end 79 which engages with and rides 50 on the periphery of an eccentric 80 carried on and rotatable with the cam-shaft 26. The rocker-arm 77 is of elbow-shape and provided with an abrupt shoulder or abutment 81 adapted to strike against the end 55 of the arm 75 of the knock-off lever 70 as shown in Fig. 3. When this engagement occurs the further movement of the rocker-arm 77 during the rotation of the eccentric 80 acts through the knock-off lever 70 to 60 rock the thread-lifter 55 to arrest the operation of the machine in the manner as later more fully explained.

The starting of the winding operation is effected through the means of a manually- 65 operated lever 85, preferably formed with a

curved handle 86 reaching out from the front of the machine through an opening 85 in the thread-lifter 55. The starting-lever 85 is pivoted on a stud 87 held in the frame-member 25, being provided with a rearwardly 70 extending arm 89 located beneath the pawl-arm 60 and formed with an upstanding looped extension 90 embracing the arm. Through this connection the lifting of the handle of the starting-lever 85 causes it to 75 depress the rearward end of the arm 60 to release its pawl 61 from the teeth 19 on the ratchet 17, see Fig. 4. The rearward arm 89 of the lever 85 carries a hardened detent-block or latch 91 which is formed with a beveled forward face adapted to engage and lock into a notch 92 on the under side of the arm 60, the purpose of this engagement being hereinafter more particularly explained. The forward arm of the starting-lever 85 carries a set-screw 93 screwed through a lug on the lever and adapted to bear against an inclined face 94 on the under side of the lug 57 which supports one end of the pivot-rod 58 for the knock-off lever 70. The set- 90 screw 93 may be adjusted to bring its end into proper relation with respect to the lug 57 and suitable checknuts 95 are provided to lock it in position. Another set-screw 96 on the forward arm of the lever 85 is ad- 95 justable to contact with the under side of the knock-off arm 75 of the lever 70 and is held in adjusted position by means of checknuts 97.

Having now described the construction 100 and arrangement of the winding machine and the present improved starting- and stopping-mechanism therefor its method of operation will next be explained.

Figs. 1 and 2 of the drawings illustrate 105 the parts of the machine in normal relation at the start of the winding operation. The cop-tube or holder *x* is shown as bearing on the periphery of the drive-roll 3 with the strand *y* of yarn, thread or other material leading up from the tension-device across the thread-bail 50 and drawing through the groove 40 in the thread-guide 35 to feed to the cop or package. The drive-roll 3 is driven continuously and as the cop-holder 2 is rotated therefrom the strand *y* is wound 110 on to the tube *x* and traversed back and forth longitudinally thereof by the constantly re- 115 ciprocated thread-guide 35.

As the yarn, thread or other material 120 builds up on the cop-tube *x* the swinging arm 5 rises to carry the cop-holder 2 away from the drive-roll 3 in the usual manner. The raising of the arm 5 turns the quadrant 16 to cause its teeth 19 to pass over and successively engage with the pawl 61 on the arm 60. It has been explained that the arm 60 is maintained in engagement with the teeth 19 on the ratchet 17 by means of the 125 spring 63 and also that the frame or thread- 130

lifter 55 to which the arm 60 is connected bears against the fixed frame-members 25. Through this arrangement the arm 60 is held in position to act as a dog to check the retrogressive movement of the arm 5 as the cop-holder 2 moves upwardly away from the drive-roll 3.

It has been noted that the trip-lever 70 is normally held with its arm 75 raised through the engagement of the strand *y* with the wire 73 on the forward arm 71 of said lever. When the strand *y* breaks or its supply is exhausted the lever 70 will be released, whereby its arm 75 will drop down into the position illustrated in Fig. 3 to cause its end to be engaged by the shoulder or abutment 81 of the rocker-arm 77. The rocker-arm 77 is constantly oscillated from the eccentric 80 on the cam-shaft 26 and as the lever 70 comes into engagement therewith the upward movement of the rocker-arm causes the tiltable thread-lifter 55 to be forced back into the position illustrated in Fig. 3. As the thread-lifter 55 is tilted back in this manner it draws the arm 60 forward and through the engagement of the pawl 61 at the end of the arm with a tooth 19 on the ratchet 17 the quadrant 16 is caused to be swung to raise the arm 5, whereby to lift the cop-holder 2 away from the drive-roll 3 to interrupt the contact between the roll and the package being wound. This action causes the arrest of the rotation of the cop-holder 2 and the rearwardly tilting action of the thread-lifter 55 acts through the thread-bail 50 to raise the strand *y* out of the groove in the thread-guide 35. In this manner the winding operation is arrested to provide for piecing up the ends of the broken yarn or furnish a new supply as the case may be.

After the thread-lifter 55 has been thrown back into the position illustrated in Fig. 3 the lever 70 will be released, as the rocker-arm 77 moves back under the turning action of the eccentric 80, and its arm 75 will drop down into the position shown by dotted lines in Fig. 3 until it engages with the stop-screw 96 on the starting-lever 85. Therefore, at the next upward movement of the rocker-arm 77 its shoulder or abutment 81 will clear the end of the arm 75 to prevent further coaction therebetween. As the arm 75 of the lever 70 drops down into this last position the thread-lifter 55 is released so that it may swing back to a slight extent until its shoulder or notch 92 is engaged by the edge of the detent-block or latch 91 on the rearward arm 89 of the starting-lever 85. The engagement of these detents acts to prevent the cop-holder 2 carried on the arm 5 from dropping back towards the drive-roll 3 and the parts remain in this position until the winding operation is restarted in the manner as next explained.

To start the winding operation the handle 86 is lifted to rock the rearward arm 89 of the lever 85 downwardly to release the pawl 61 on the arm 60 from the ratchet 17 on the quadrant 16. As the handle 86 is raised, as shown in Fig. 4, the looped extension 90 on the arm 89 of the lever 85 tilts the arm 60 downwardly to release its end from the quadrant 16 whereby the arm 5 is allowed to swing downwardly under the action of gravity to replace the cop in contact with the surface of the drive-roll 3. This lifting action of the handle 86 also removes the detent-block 91 from engagement with the notch 92 on the arm 60, but the thread-lifter 55 is initially prevented from swinging back into first position through the coaction of means operating in the manner as next explained. It has been stated that the present improved starting-mechanism is designed to prevent premature stopping of the winding operation after it has once been started and this result is obtained by restraining the thread-lifter 55 from returning to position in which the trip- or knock-off lever 70 may be engaged by the rocker-arm 77. As the cop is lowered into contact with the drive-roll 3 driving action thereof will be resumed, but before the strand has been picked up by the thread-guide 35 and the slack taken up by the winding operation there is danger of premature stopping of the machine and hence the action of the stopping-mechanism is restrained for a period until the strand has been drawn tight. This control of the stopping-mechanism is permissive under the manipulation of the starting-lever 85, the operator holding the handle 86 of the lever raised until the winding operation has been properly started. That is to say, the handle 86 is held for an instant in raised position whereby the engagement of its set-screw 93 with the inclined face 94 on the thread-lifter 55 retains the latter in the position illustrated in Fig. 4 to prevent it from swinging back towards the thread-guide 35. After the operator is satisfied that the machine is properly operating and the slack in the strand *y* has been taken up to cause the trip-lever 70 to rock back into the position shown in Fig. 2, the handle 86 may be released. The release of the handle 86 allows the rearward arm 89 of the lever 85 to be rocked upwardly under the force of the spring 63 acting on the arm 60 to carry it back into position to engage the pawl 61 with the ratchet 17 on the quadrant 16. The parts of the stopping-mechanism are thus returned into normal relation as shown in Fig. 1 with the trip- or knock-off lever 70 held suspended by the strand *y* to prevent its rearward arm 75 from contact with the shoulder 81 on the rocker arm 77.

It will be observed from the foregoing that my invention provides an improved

form of stopping-mechanism which is under control of the operator during the starting of the machine to prevent premature or unwarranted arrest of the winding operation.

5 The mechanism of the device is simple in construction, positive in action, and proof against derangement, while being of greater durability than similar devices now in use. The arrangement for preventing unwarranted engagement between the knock-off devices at the start of the winding, besides guarding against premature stopping of the machine, also eliminates undue wear and strain on the parts of the stopping-mechanism.

10 While I have shown my invention as embodied in a certain type of machine and comprising a preferred form of construction, it is to be understood that various modifications may be made in the form and arrangement of the parts of the device without departing from the spirit or scope of the invention as expressed in the appended claims. Therefore, without limitation in 15 this respect, I claim:

1. In a winding machine, the combination of a drive-roll, a cop-holder on which the cop is wound through contact with the drive-roll, means for traversing strand material on the cop-holder, a ratchet movable with the cop-holder during the growth in the winding, means engaging said ratchet for moving the cop away from the drive-roll to arrest the winding, a trip-lever connected with said ratchet-engaging means and normally engaging the strand feeding to the cop-holder, means adapted to actuate said trip-lever upon its release by the strand to cause it to move the ratchet-engaging means, detent-means acting on the ratchet-engaging means to hold the cop away from the drive-roll, a starting-lever for releasing the ratchet-engaging means to permit the return of the cop into contact with the drive-roll, and means operated from said starting-lever to restrain the trip-lever from action while the strand is slack at the start of the winding.

2. In a winding machine, the combination of a drive-roll, a cop-holder on which the cop is wound through contact with the drive-roll, means for supporting the cop-holder to adapt it to recede from the drive-roll as the cop increases in diameter, a ratchet movable with the cop-holder supporting-means, an arm engaging the teeth of the ratchet to prevent retrogressive movement of the cop-holder, a trip-lever connected to said arm and normally suspended by the strand feeding to the cop-holder, means for operating the trip-lever when the latter is released by the strand to cause it to move the arm to act through the ratchet to remove the cop from contact with the drive-roll, and manually-controlled means for re-

leasing the arm from the ratchet to cause the cop to be returned into contact with the drive-roll.

3. In a winding machine, the combination of a drive-roll, a cop-holder on which the cop is wound through contact with the drive-roll, means for supporting the cop-holder to adapt it to recede from the drive-roll as the cop increases in diameter, a ratchet movable with the cop-holder supporting-means, an arm having a pawl engaging the teeth on the ratchet to prevent retrogressive movement of the cop-holder, a trip-lever pivoted to said arm and normally suspended through engagement with the strand feeding to the cop-holder, means adapted to actuate the trip-lever when the latter is released from the strand to cause it to move the arm to operate the ratchet to remove the cop from contact with the drive-roll, a starting-lever provided with a detent for engaging the arm to lock it in position to prevent the cop from returning into contact with the drive-roll, and means operated from said lever to release the arm from the ratchet to allow the cop to return into contact with the drive-roll.

4. In a winding machine, the combination of a drive-roll, a cop-holder on which the cop is wound through contact with the drive-roll, means for supporting the cop-holder to adapt it to recede from the drive-roll as the cop increases in diameter, a ratchet carried by said cop-holder supporting-means, a slidable arm engaging said ratchet, a trip-lever pivoted on said arm to adapt it to be suspended through engagement with the strand feeding to the cop-holder, means acting on the trip-lever when the latter is released by the strand to cause it to slide the arm to operate the ratchet to remove the cop from contact with the drive-roll, a pivoted starting-lever provided with means engaging the arm to release it from the ratchet to cause return of the cop into contact with the drive-roll, and means operated from said lever to restrain the trip-lever from action before it is carried into suspension by the strand.

5. In a winding machine, the combination of a drive-roll, a cop-holder on which the cop is wound through contact with the drive-roll, means for supporting the cop-holder to adapt it to recede from the drive-roll as the cop increases in diameter, a ratchet on said supporting-means, an arm engaging the ratchet to prevent retrogressive movement of the cop-holder, a trip-lever pivoted to said arm and adapted to be suspended by the strand feeding to the cop-holder, means acting on the trip-lever when the latter is released by the strand to cause it to move the arm to carry the cop out of contact with the drive-roll, a starting-lever provided with a detent engaging the arm to lock it in posi-

tion to prevent return of the cop into contact with the drive-roll, said lever also having means for releasing the arm from the ratchet to permit return of the cop into contact with the drive-roll, and means operated from the initial movement of the starting-lever to restrain the trip-lever from action at the start of the winding.

6. In a winding machine, the combination 10 of a drive-roll, a cop-holder on which the cop is wound through contact with the drive-roll, means for removing the cop from contact with the drive-roll to arrest the winding operation including a ratchet, an arm engaging said ratchet, a trip-lever pivoted to said arm and adapted to be suspended by the strand feeding to the cop-holder, means operative upon the release of the trip-lever to move the arm to operate the ratchet to 15 carry the cop out of contact with the drive-roll, a rockable starting-lever having a detent engageable with the arm to prevent the cop from returning into contact with the drive-roll, said starting-lever also provided 20 with means for releasing the arm from the ratchet to allow return of the cop into contact with the drive-roll, and means carried by the starting-lever and acting when the latter is rocked to release the arm from the 25 ratchet to prevent operation of the trip-lever.

7. In a winding machine, the combination 30 of a drive-roll, a cop-holder on which the cop is wound through contact with the drive-roll, a thread-guide for traversing strand material on the cop-holder, stopping-mechanism for removing the cop from contact with the drive-roll to arrest the winding operation, a thread-lifter operated from the 35 stopping-mechanism to disengage the strand from the thread-guide when the cop is removed from contact with the drive-roll, means engaging the strand as it feeds to the drive-roll and adapted to operate when released thereby to cause operation of the 40 stopping-mechanism, starting-means for returning the cop into contact with the drive-roll and the thread-lifter into operative relation with the thread-guide, and means operated from said starting-means to prevent 45 operation of the strand-controlled means to prevent premature action of the stopping-mechanism at the start of the winding.

8. In a winding machine, the combination 50 of a drive-roll, a cop-holder on which the cop is wound through contact with the drive-roll, a thread-guide for traversing strand material on the cop-holder, stopping-mechanism for removing the cop from contact

with the drive-roll, a thread-lifter operated 60 from the stopping-mechanism to disengage the strand from the thread-guide, a trip-lever suspended by the strand feeding to the cop-holder and adapted when released thereby to cause operation of the stopping-mechanism, a starting-lever for releasing the 65 stopping-mechanism to start the winding operation, and means on the starting-lever for preventing action of the trip-lever when the strand is slack at the start of the winding. 70

9. In a winding machine, the combination 75 of a drive-roll, a cop-holder on which the cop is wound through contact with the drive-roll, a thread-guide for traversing strand material on the cop-holder, a ratchet connected to be moved from the cop-holder as the latter recedes from the drive-roll during the growth in the cop, an arm engaging said ratchet, a rockable thread-lifter connected to said arm and normally disposed adjacent 80 the thread-guide, a trip-lever adapted to be suspended by the strand feeding to the cop-holder, means engaging the trip-lever upon its release by the strand to cause it to move the arm to remove the cop from contact with 85 the drive-roll and to rock the thread-lifter to disengage the strand from the thread-guide, detent-means for locking the arm in position with the cop removed from contact with the drive-roll, and a starting-lever for 90 disengaging the detent-means and releasing the arm from the ratchet.

10. In a winding machine, the combination 95 of a drive-roll, a cop-holder on which the cop is wound through contact with the drive-roll, a swinging arm for supporting the cop in contact with the drive-roll, an arcuate ratchet carried by said arm, a thread-guide for traversing strand material on the cop-holder, a rockable thread-lifter normally 100 maintained in position adjacent the thread-guide, an arm connected with the thread-lifter and provided with means for engaging the teeth on the ratchet, a trip-lever suspended by the strand feeding to the thread-guide, means adapted to engage the trip-lever when the latter is released by the strand to slide the arm to rock the thread-lifter and to act through the ratchet to remove the cop from contact with the drive-roll, a detent for locking the arm in position after its sliding movement, and a starting-lever for releasing the detent and disengaging the arm from the ratchet. 110

In testimony whereof I hereunto affix my 115 signature.

CHARLES H. JONES.
